ELECTRIC STEAM IRON

Joseph O. Thibault, Bridgeport, Conn., assignor
to Casco Products Corporation, Bridgeport,
Conn., a corporation of Connecticut

Application May 16, 1950, Serial No. 162,177

5 Claims. (Cl. 38—77)

1

This invention relates to steam irons, particularly electric steam irons of the type manufactured for domestic use, in the home.

Heretofore electric steam irons of the above type have generally adhered to a structural design characterized by the boiler, which was mounted above the sole plate, also constituting the casing of the iron. These boiler-casings were either made as castings of aluminum or the like, or as composite sheet-metal structures employing welding, soldering or similar fastening means in their fabrication.

Presumably the purpose behind such prior designs was to obtain a large water capacity, together with simplicity of construction and economy of manufacture.

One prior type of composite sheet-metal boiler construction consisted of an upper section in the form of a dished drawn sheet-metal shell having the usual dome-like casing shape with a depending skirt engaging the sole plate, and a cooperable lower section comprising a bottom plate provided along its edge portions with downturned or outturned flanges engaging the inner upright walls of the skirt of the upper or casing section. The engaging portions of the two sections, which were in overlapping relation, were then seam-welded together. This procedure marred the outside surfaces of the skirt of the casing section, and produced a difficult problem in the matter of finishing the casing. This problem was aggravated by the fact that the casing sections were made of stainless steel, which is particularly resistant to polishing and finishing operations where pockets are formed and appreciable material has to be removed to provide smooth surfaces.

As a consequence, the matter of finishing the boiler-casing assembly was time-consuming and expensive, and not conducive to quality finishing. Moreover, with this prior type of construction there was another significant disadvantage in that the portions to be seam-welded did not lie in a single, flat plane, but instead followed a curved, devious path necessitating turning and twisting of the assembly during the welding. This was not only difficult, time-consuming and costly, but often resulted in imperfect welds, causing leaky boilers in which the defects had to be first located and then corrected. A further difficulty arose if the boiler-casing developed defects after being put into service. Where such defects involved leakage, which was often the case, the boiler-casing assemblage would have to be removed and replaced by a complete new

2

assemblage, which was usually done at a service or field station. This caused quite appreciable expense to the customer, since the replacement did not involve simply a boiler but instead also involved a highly finished casing part, produced at relatively great cost due not only to its being made of stainless steel but also because the welding formed pockets in the outer surface, which had to be removed by the finishing process.

10 In another prior type of iron a composite stainless steel combined casing and boiler was formed of an upper section comprising a dome-shaped shell constituting the casing and a cooperable lower section comprising a bottom and back plate, which had upturned and inturned flanges around its edge portions, engaging the inner- and undersurfaces of the top section. In this particular prior art construction silver solder was used to join together the two sections. While this eliminated the pitting of the outer surfaces of the upper or casing section, it was not particularly well adapted to simple and rapid, economical production and did not completely remedy the leakage problem (requiring subsequent correcting operations), nor the high cost of finishing a stainless steel casing part, nor the high cost of replacement if the casing-boiler assembly developed defects after being put into use.

15 The present invention overcomes the difficulties and disadvantages of these prior constructions mentioned above, it being an object of the invention to provide an improved electric steam iron of exceptional quality and sturdy and rugged construction, characterized by reliable performance and large water capacity while at the same time being simple to construct and manufacture, and easy and economical to service.

20 In accomplishing this object I have departed from the usual and accepted procedure followed 30 in the past, of making the boiler and casing as a single unit. Instead, I make the boiler and casing as separate units, the boiler being formed of sheet-metal sections secured together, and the casing of a separate dome-shaped sheet-metal 35 shell adapted to overlie and surround the boiler. I have found that by so doing, contrary to expectations, desirable economies in the finishing operations of the casing and in the fabrication, particularly the welding, of the boiler may be 40 effected. The welding, besides being quicker and less costly, is more effective, thereby eliminating leaks and reprocessing and providing greater reliability in boiler performance and life. In addition, servicing of the iron is made easier, and 45 boiler replacement is less costly.

By the present invention, the construction and arrangement of the boiler may be worked out without regard to its finish and appearance, so that the factors of ease and reliability in the welding of the boiler sections may be given the fullest consideration. The casing according to the present invention may be separate from the boiler, and may be made of a metal different from stainless steel or other metals which are difficult to finish and are rust and corrosion resistant. The casing metal may be chosen for its ease and economy in forming and finishing.

I have found it advantageous to form the boiler of upper and lower, facing, dished sections, each section comprising a sheet-metal shell having a rim including an outturned flange disposed in a single, flat plane. The flanges have continuous circumferential overlapping portions, and are secured together in water-tight relation to form a vessel. Thus there may be employed a quick and economical, continuous seam-welding procedure, which may be done on semiautomatic equipment, producing a highly efficient seam or joint which is completely water-tight and also reliable in use even though subjected to stresses imposed by the manipulating of the iron.

I have found that the welded joint formed by the outturned flanges which are disposed in flat planes, overlapping each other, is so sturdy and rugged that advantage may be taken of this fact to anchor the lower section of the boiler to the sole plate and to mount the handle of the iron indirectly on the upper boiler section. Such construction is adequately rigid and strong, and has the advantage of enabling the upper portions of the boiler and casing to be secured together to eliminate additional fastenings between the casing and sole plate. This simplification of the fastening means is of advantage not only in the manufacture of the iron, but when it becomes necessary to dismantle the iron to carry out servicing operations.

By making the casing and boiler separate and distinct from each other, not only can the casing be economically finished because it can be made of metal different from the rust-proof metal of the boiler, but in the event that at a later date the boiler shows some defect and requires replacement, the cost of such replacement will be relatively low because it does not involve the discarding of a finished casing, as was heretofore the case.

The invention is embodied in an iron of the type having a pivoted handle which can be swung back from operative position to expose the filler opening for the boiler, and in connection with this organization I dispose the fastening means for the casing so as to be normally concealed by the handle, and to be exposed when the handle is swung back to filling position, thereby simplifying the dismantling of the iron when servicing is necessary.

In order to obtain relatively large water capacity I trim the welded outturned flanges of the boiler after the welding thereof, to reduce the width of the flanges to a relatively small figure. Accordingly the side walls of the boiler may be brought into close proximity to the side walls of the casing, reducing the unused space between the boiler and casing, and enabling a relatively large boiler capacity to be obtained for a given casing size. Moreover, by the provision of the aforesaid space between the boiler and the casing, the latter functions as an effective shield, being maintained at a relatively

cool temperature whereby it is not so hot to the touch and not so likely to cause burns or discomfort if a user should inadvertently come in contact with the casing.

I utilize the welded flanges of the boiler as part of the means for securing the boiler to the casing, thereby providing an extremely simple and reliable mounting.

Other features and advantages will hereinafter appear.

In the accompanying drawings:

Figure 1 is a vertical, longitudinal sectional view of an electric steam iron embodying the invention.

Fig. 2 is an enlarged fragmentary detail of the steam dome and upper portions of the boiler and casing, illustrating the means for fastening the casing to the boiler.

Fig. 3 is an enlarged fragmentary detail of the filler opening of the boiler, showing the gasket-type sealing means interposed between the boiler and the casing.

Fig. 4 is a rear elevational view of the iron, with portions broken away and shown in section to illustrate interior details.

Fig. 5 is a top view of the casing of the iron.

Fig. 6 is a top view of the complete sheet-metal boiler.

Fig. 7 is a side elevational view of the boiler.

Fig. 8 is a top view of the boiler after assembly and welding of the parts, but prior to trimming off excess material, and

Fig. 9 is a plan view of a heat-conducting shim such as is interposed between the sole plate and boiler, and between the sole plate and thermostat.

The iron embodying the invention, as shown in Fig. 1, comprises a sole plate 10 having an electric heating element 11 connected with a thermostat 12 which is mounted on the rear portion of the sole plate. The thermostat 12 is of the usual type, having a frame 13 mounting contacts 14 and 15, the latter contact being actuated by a lever 16 engaged by a low expansion strip 17 which is secured to a high expansion strip 18 attached to the frame 13.

Adjustment of the thermostat 12 is provided for by a knob 19 carried on a shaft 20 which engages the contact 14 and is threaded into a sleeve 21 carried by the frame 13.

At the front of the sole plate 10 a steam chamber 22 is provided, enclosed by a cover plate 23 into which there is threaded an upright steam tube 24 having an extension 24a of reduced diameter. The steam tube 24 has notches 25 in its end, to accommodate a wrench.

In accordance with the invention a novel assemblage of sheet-metal boiler and separate sheet-metal casing is provided, in conjunction with the sole plate 10, to produce a superior quality steam iron characterized by low manufacturing cost, high performance and reliability, ease of disassembly and servicing, and low-cost boiler replacement should this ever be necessary.

As shown in Figs. 1, 6, 7 and 8, the boiler of this assemblage, indicated by the numeral 25, comprises a dished, upright, lower sheet-metal section 26 and a dished, inverted, upper sheet-metal section 27. The sections 26 and 27 are shaped and formed by the usual punches and dies and after leaving the tools have the configurations shown in Fig. 8, with irregular shaped, outturned flanges 28 and 29. In assembly, the boiler sections 26 and 27 are placed together with their flanges in engagement and subjected

to a seam-welding operation which joins the flanges together closely adjacent the walls of the sections. After this, the assembled sections are placed in a trimming tool, and the excess material removed from the flanges, leaving the configurations shown in Figs. 6 and 7, including apertured mounting ears or lugs 30.

Prior to the assembly of the boiler sections, the upper section 27 is provided with a filler opening 31 having a valve seat 32 depending therefrom. The valve seat 31 may be advantageously made of a drawn sheet-metal cup, and may have a crimped flange 33 and a second flange 34 between which the upper wall 35 of the boiler is securely gripped.

Also, prior to assembly of the boiler sections, the upper section 27 is provided with a second opening 36 in its front upper portion, around which a hollow threaded boss 37 is secured. As will be seen in Fig. 1, the extension 24a of the steam tube 24 passes upwardly through the boss 37 and projects above the top of the boiler 25. Between the openings 31 and 36 of the boiler a depressed portion 38 is provided, to provide clearance for a latching structure as shown in Fig. 1.

Enclosing the boiler 25 and secured to it is a dome-shaped casing 39 in the form of an elongate shell, which is also drawn of sheet-metal. The bottom edge or rim 40 of the shell engages the edge portions of the sole plate 10, being received in a peripheral recess 41 provided for this purpose. The front upper portion of the casing 39 is provided with an opening 42 through which the boss 37 of the boiler extends, and a steam dome 43 in the form of a drawn sheet-metal 35 thimble is threaded onto the boss 37 so as to enclose the upper portion of the steam tube extension 24a and to securely fasten together the adjacent upper portions of the boiler 25 and casing 39. For this latter purpose, the steam dome 43 has an outturned flange 44 engaging a washer 45 which surrounds the boss 37 and rests on the casing 39.

Referring to Figs. 1, 4 and 6, the apertured lugs 30 of the boiler 25 receive screws 46, which are threaded into upstanding bosses 47 on the sole plate 10, thus fastening the rear portion of the boiler to the sole plate.

The rear central part 48 of the casing 39 is depressed. It has a downward and backward sloped flat portion 49, merging with a horizontal edge portion 50 which terminates in a transverse depending flange 51. The horizontal edge portion 50 at its center extends forwardly at 52 and is provided with a screw hole 53. A steep sloping wall 54 joins the portions 49 and 52 together. As seen in Fig. 1, a screw 55 passes through the hole 53 and is threaded into a boss 56 on the sole plate 10 for the purpose of securing the casing 39 to the sole plate. In order to steady the casing on the sole plate without employing additional fastenings, two upright bosses 56a are provided on opposite sides of the boss 56 and spaced therefrom a substantial distance, the bosses 56a engaging the underside of the horizontal edge portion 50 of the casing. To provide clearance for the thermostat shaft 20, the portion 49 of the casing is provided with an aperture 57 substantially larger than the shaft.

In order to obtain a steady, smooth-acting bearing for the shaft 20 a bearing bracket 58 is provided, in accordance with the invention, having an opening 59 through which the shaft passes and against the walls of which it bears. The bracket 58 has apertured ears 60 through which

fastening screws 61 pass, said screws being threaded into the upper wall portion 49 of the casing.

The top of the casing 39 has a large central opening 62 which is aligned with the filler opening 31 of the boiler. Around the edge of the opening 62 a depending flange 63 is provided, and encircling the flange 63 is a washer or gasket 64, interposed between the top walls of the casing 10 and boiler to provide a seal and prevent water from leaking between the casing and boiler when the latter is being filled.

The casing 39 has at its rear a pair of inwardly facing walls 65 which are apertured to receive 15 spring loaded trunnion pins 66 carried in the rear portion 67 of a handle structure 68. The handle structure 68 is similar generally to that shown and described in my copending application Serial No. 103,437, filed July 7, 1949, entitled "Steam 20 Electric Iron." It consists of a broad flat base plate 69 having upstanding front and rear posts 70 and 71 respectively which are connected together at their tops by a handle proper 72. The rear post 71 has a recess 73 to accommodate the 25 thermostat knob 19, and the front post 70 has a recess 74 to accommodate the steam dome 43.

As shown in Fig. 1, the handle structure 68 may be swung backward to a filling position indicated by the broken lines. When in this position it exposes the filler opening 31 of the boiler 25. On the underside of the base 69 of the handle a valve seat 32 carried by the upper wall of the boiler 25.

To releasably lock the handle structure 68 in operative position a latch 76 is provided.

For the purpose of reinforcing the top wall of the boiler 25 around the filler opening 31 thereof, so as to minimize distortion of said wall by pressure imposed upon it by the closure 75, reinforcing ribs 77 are embossed in the boiler wall, Fig. 6. These ribs prevent the boiler wall and casing wall from separating at the gasket 64, and maintain the gasket in tight sealing relation with the said walls.

45 It will be seen that by the above construction the handle structure 68 is secured to the casing 39 at the rear by the trunnions 66, and to the forward portion of the casing by the releasable latch 76. The casing 39, in turn, is secured to the sole plate 10 at the rear thereof by the single screw 55, and at the front is not fastened directly to the sole plate but instead to the top forward portion of the boiler 25 by means of the steam dome 43.

55 I have found that, by making a composite boiler of sections having outturned flanges lying in substantially flat planes, and seam-welding the flanges together, an extremely strong and sturdy unitary structure results which will not develop weakness or failure even with the handle transmitting force to the sole plate through the forward portion of the boiler. The casing 39 is nowhere at its forward portion secured directly to the sole plate. Instead, it is secured to the upper portion of the boiler, and the lower forward portion of the boiler is secured to the sole plate by the steam pipe 24. Thus, as a consequence of effecting a strong weld between the boiler sections 26 and 27, I have obviated the necessity of securing the casing 39 directly to the sole plate at the front of the iron. Accordingly I have accomplished a simplification of the fastening means, resulting in a desirable economy in manufacture and assembly of the iron, and

simplifying the dismantling of the iron for servicing or replacement of the boiler.

Moreover, by making the boiler 25 separate from the casing 39, replacement of the boiler may be effected without requiring replacement of the highly finished casing part 39. Thus, the customer in the event of failure of the boiler, need not pay for a finished casing part, but instead only for a boiler as such. Since the boiler does not have a highly finished surface which is expensive to produce, its initial cost is relatively low and as a result replacement of the boiler does not involve an appreciably high expense.

Since the boiler 25 and the casing 39 are entirely separate from each other, the material for the boiler may be chosen from any of various rust- and corrosion-resistant metals without regard to the problem of finishing, and the material of the casing may be chosen primarily or largely with regard to the finishing. In addition, since there is no welding involved in the construction of the casing 39, to cause pockets or markings on the exterior surface, the finishing of the casing may be done quickly and economically.

Considering the boiler itself, the provision of the flat flanges 28 and 29 enable the boiler sections to be seam-welded together at the flanges by semiautomatic equipment, and it is not required that the boiler be twisted or maneuvered along an intricate curved path during the welding operation. Accordingly the welding may be carried out quickly and economically, and may be made very effective to provide completely watertight joints at the flanges.

By virtue of the flanges 28 and 29 being trimmed off close to the side walls of the boiler 25 after the welding, the boiler walls and casing walls may be brought into close proximity, minimizing the amount of space not utilized for water between the boiler and casing walls and resulting in a relatively large boiler capacity. The relatively small air space which does exist between the walls of the boiler and the casing, however, provides an effective heat insulator to prevent the casing from becoming as hot as the walls of the boiler. Thus the likelihood of a user becoming burned if he inadvertently touches the casing is considerably reduced.

Because of the simplified welding procedure by which the boiler of this invention may be fabricated, together with the ease and rapidity of finishing the casing surrounding the boiler, I have effected a desirable economy in the manufacture of the iron. Contributing to this also is the effectiveness of the welding, which minimizes leakage defects and subsequent corrective processing operations, and the simplification of fastening means by which the sole plate, boiler and casing are secured together.

In order to provide a more efficient heat transfer from the sole plate 10 to the boiler 25 I provide, in accordance with this invention, fluted or ribbed shims 78, Figs. 1 and 9, which are interposed between the bottom wall of the boiler and the top wall of the sole plate along the area disposed directly over the heating element 11.

Referring to Fig. 4, an improved cord anchorage is provided to securely fasten the supply cord 79 to the iron at the point where it passes through the wall of the casing 39. This cord anchorage comprises an externally threaded hollow boss or bushing 80, which is mounted on the casing 39, said bushing having a tapered bore 81. The electric cord 79 passes through the bushing 80 and is engaged and gripped by spring fingers 82 ex-

tending from a flat washer-like body 83 subjected to forces exerted by a cap 84 threaded on the bushing 80. The fingers 82 are forced longitudinally inward against the tapered bore 81 of the bushing when the cap 83 is tightened, thus forcing the fingers inward against the cord 79 to securely grip the latter.

A helical wire-cord protector 85 is provided on the cord 79, one end 86 of the protector having an enlarged diameter and fitting within the cap 84 to be held thereto by an inner flange 87 on the cap.

Variations and modifications may be made within the scope of the claims and portions of the improvements may be used without others.

I. claim:

1. In a steam iron, a sole-plate; a boiler disposed above the sole plate; a shell-like casing having a top and depending sides enclosing the boiler; removable means engaging the forward interior bottom portion of the boiler, releasably securing the forward bottom portion to the sole plate; means releasably securing the rear of the boiler to the sole plate; means independent of both said preceding means, releasably securing the rear of the casing to the sole plate; and means releasably securing the forward upper portions of the boiler and casing together, said casing and boiler being separable from the sole plate and from each other whereby replacement of the boiler may be readily effected.

2. In a steam iron, a sole plate; a boiler disposed above the sole plate; a shell-like casing having a top and depending sides enclosing the boiler; removable means engaging the forward interior bottom portion of the boiler, releasably securing the forward bottom portion to the sole plate; means releasably securing the rear of the boiler to the sole plate; means independent of both said preceding means, releasably securing the rear of the casing to the sole plate; and means releasably securing the forward upper portions of the boiler and casing together, said casing portion having an opening and said means including a bushing passing through said opening and a steam dome removably attached to the bushing and projecting upwardly from the casing, said casing and boiler being separable from the sole plate and from each other whereby replacement of the boiler may be readily effected.

3. The invention as defined in claim 1, in which the means for fastening the rear of the casing to the sole plate comprises solely a centrally located screw passing through a top wall of the casing and threaded into the sole plate, and in which the sole plate has means engaging the undersurface of the casing top wall on opposite sides of said screw, for steadyng the casing.

4. In a steam iron, a sole plate; a boiler mounted on the sole plate; a casing enclosing the top and sides of the boiler; means releasably fastening together the front upper portions of the boiler and casing; means releasably fastening the rear of the casing to the sole plate; a handle disposed above the casing, having means overlying and concealing both said fastening means; and means securing the handle in operative position on the casing, said handle securing means being manually releasable to enable the handle to be shifted out of operative position to expose both said fastening means.

5. In a steam iron, a sole plate; a sheet-metal boiler secured to the sole plate; a casing comprising a sheet-metal shell enclosing the boiler, said casing and boiler having aligned openings

in superposed upper portions to enable the boiler to be filled; gasket means disposed between and sealing the edge portions of both the openings of the boiler and casing to prevent leakage of fluid therebetween, said casing having a down-turned flange around the opening in its top portion, extending into said gasket means and positioning the same; and means remote from said gasket means, securing the casing to the sole plate and maintaining the gasket means under compression to preserve said seal.

JOSEPH O. THIBAULT.
